UNITED STATES PATENT OFFICE.

PAUL J. STUPARICH, OF SAN FRANCISCO, CALIFORNIA.

DESIGN FOR A PHOTOGRAPHIC MOUNT.

SPECIFICATION forming part of Design No. 31,213, dated July 11, 1899.

Application filed May 2, 1899. Serial No. 715,377. Term of patent 7 years.

To all whom it may concern:

Be it known that I, PAUL J. STUPARICH, a citizen of the United States, residing in the city and county of San Francisco, State of California, have invented and produced a new and original Design for Photographic Mounts, of which the following is a specification, reference being had to the accompanying drawing, forming part thereof.

As shown in the drawing, the leading feature of my design consists of a border of raised lines or ribs A, radially disposed from the periphery of the central space, within which the picture is to be mounted. Surrounding this space and intermediate between it and the radial lines is a plain border B, and from the periphery of this border the lines extend out-

wardly and are made of different lengths, so that their outer ends form a wavy or serrated outline, as shown at C. Exterior to the raised ribs or lines the remainder of the surface of the card is plain.

Having described my invention, what I claim as new, and desire to secure by Letters Patent, is—

The design for a photographic card-mount as herein shown and described.

In witness whereof I have hereunto set my hand.

PAUL J. STUPARICH.

Witnesses:

WM. J. HELMQUEST,
H. ADAMS.
